CLAIM

The ornamental design for a beer glass, as shown and described.

DESCRIPTION

FIG. 1 is a perspective view of a first embodiment of a beer glass showing our new design;

FIG. 2 is a front view thereof, the rear view, left side view, and right side view being a mirror image thereof;

FIG. 3 is a top view thereof;

FIG. 4 is a bottom view thereof;

FIG. 5 is a perspective view of a second embodiment of a beer glass showing our new design;

FIG. 6 is a front view thereof; the rear view, left side view and right side view being a mirror image thereof;

FIG. 7 is a top view thereof; and,

FIG. 8 is a bottom view thereof.
